UNITED STATES PATENT OFFICE.

CHRISTIAN C. ZARS, OF ADDISON, ILLINOIS.

LEVEL.

1,110,026.

Specification of Letters Patent.

Patented Sept. 8, 1914.

Application filed September 18, 1913. Serial No. 790 518.

To all whom it may concern:

Be it known that I, CHRISTIAN C. ZARS, a citizen of the United States, residing at Addison, in the county of DuPage, State of Illinois, have invented certain new and useful Improvements in Levels; and I do hereby declare the following to be a full, clear, and exact description of the invention, such as will enable others skilled in the art to 10 which it appertains to make and use the same.

This invention relates to levels and has for an object to provide a device of this character that will indicate the angle of the 15 surface against which the level is placed, from the horizontal.

A further object of the invention is to provide an extremely simple and inexpensive device of this character that will be accurate and reliable, and will be formed of 20 a few parts that will not easily get out of order.

With the above objects in view the invention consists of certain novel details of construction and combinations of parts herein-after fully described and claimed, it being understood that various modifications may be made in the minor details of construction within the scope of the appended claim.

30 In the accompanying drawing illustrating this invention:—Figure 1 is a front elevation of the level. Fig. 2 is a cross sectional view taken on the line 2—2 of Fig. 1. Fig. 3 is a fragmentary longitudinal sectional view with parts removed showing the removable cap for facilitating access to the interior of the level. Fig. 4 is a detail perspective view of the two piece shaft. Fig. 5 is a detail perspective view of the weight 40 and its attaching means. Fig. 6 is a detail perspective view of one of the pointers and its attaching means.

Referring now to the drawing in which like characters of reference designate similar parts, 10 indicates the body of the level, which has the usual straight edge 11. The body is formed with a central enlargement 12 through which there is formed a cylindrical opening 13, the enlargement projecting beyond the upper edge of the body in semi-circular form as shown. The central enlargement 12 is provided with a longitudinal slot in which is removably mounted a closure 14 so that access to the interior of 55 the opening 13 may be had. At each end of the opening there is a glass disk, as shown

at 15 and 16, such disks having the outer edges beveled as shown at 17 to fit against beveled shoulders 18 formed to project inwardly of the outer edges of the circular 60 opening 13. These disks are formed with central conical sockets 19 to receive the conical ends of a two-piece shaft 20 that is formed square in cross section, the sections of the shaft being joined together by a substantially square sleeve 21 which receives 65 said sections, and carries set screws 22 which rigidly secure the sections together and hold the shaft in such length as to confine the disks 15 and 16 snugly in place. Upon loosening the set screws the sections of the shaft may be telescoped into the sleeve to withdraw the shaft and also the disks through the edge of the enlargement 12 upon removal of the section 14 thereof.

70 The sleeve 21 is equipped with an anchor-shaped weight 23 that performs the function of a plumb bob. Fixedly attached to the square ends of the shaft are pointers 24 and 25 each being equipped at the base with a 80 sleeve 26 of substantially square cross section, there being a set screw 27 carried by the sleeve and engaging against the shaft to hold the pointer in place.

Arranged on opposite sides of the weight, 85 are dials 28 and 29 the peripheral edges of which are seated in grooves in the interior wall of the cylindrical opening 14, these dials each having a central opening 30 which receives the shaft. The dials may be marked 90 with scales indicating degrees and fractional parts thereof.

In operation, the level is placed upon the surface of a wall or other article as usual, whereupon should the surface not be exactly level or plumb, the variation of the 95 surface will be indicated on the scales by the pointers.

From the above description it will be seen that I have provided an extremely simple 100 and inexpensive level that will be effective in operation, and will be formed of a few parts that will not easily get out of order.

What is claimed, is:—

105 A level including a body having an enlarged intermediate portion provided with a transverse cylindrical passage therethrough and having a longitudinal slot therein communicating with the passage; a removable closure for said slot, a shoulder 110 at each end of the passage, glass disks closing the ends of said passage, a contractible

shaft journaled at its end in said disks beneath said slot and holding said disks against said shoulders, a depending weight upon said shaft, pointers on the shaft, and 5 dials provided with scales confined in said opening in the rear of said pointers.

In testimony whereof, I affix my signature, in the presence of two witnesses.

CHRISTIAN C. ZARS.
